UNITED STATES PATENT OFFICE.

HARRY A. TRUSCOTT, OF WASHINGTON, DISTRICT OF COLUMBIA.

PARCEL-POST ENVELOP.

1,154,276.

Specification of Letters Patent. Patented Sept. 21, 1915.

Application filed November 10, 1914. Serial No. 871,371.

To all whom it may concern:

Be it known that I, HARRY A. TRUSCOTT, a citizen of the United States, residing at Washington, in the District of Columbia, 5 have invented new and useful Improvements in Parcel-Post Envelops, of which the following is a specification.

This invention relates to improvements in envelops; and particularly to an envelop, 10 which while like or similar to the envelop in general use, includes or is provided with means for attaching it to a parcel post package in accordance with established regulations.

15 The object of the invention is to provide an envelop having means for reinforcing an end of the envelop in an effective manner and fastening means, engaging and secured in position by said reinforcing means and projecting exteriorly of such end of the envelop, whereby the envelop may be secured in a firm and substantial manner to a package; or the device or means for reinforcing the end of the envelop, including the fastening means, may be manufactured separately 20 from the envelops and sold ready for application to an ordinary envelop by any person at will.

25 The invention consists of the features of construction, combination and arrangement of parts herein fully described and claimed, reference being had to the accompanying drawing in which:—

30 Figure 1 is a front view of an envelop embodying my invention. Fig. 2 is a horizontal transverse section on line 2—2 of Fig. 1. Fig. 3 is a vertical section on line 3—3 of Fig. 2 through the envelop. Fig. 4 is a perspective view of the reinforcement and fastener detached. Figs. 5 to 9 inclusive, are perspective views of different forms 35 of reinforcements and fasteners which may be employed.

40 Referring to the drawing, 1 designates an envelop of conventional form, and of that type having a top sealing flap 2. As shown, in the form of my invention illustrated in Figs. 1 to 4, inclusive, the envelop is provided at one end with a reinforcement 3, 45 arranged at the fold line or point of intersection of the front and back walls 4 and 5. This reinforcement consists of an oblong rectangular strip of flexible material, such as cloth or cardboard, or any other suitable 50 fabric, which is folded longitudinally along

a medial line, as shown at 6 to provide opposed flaps 7, the said fold line 6 coinciding with the angle of intersection or line of fold 8 between the said front and back walls 4 and 5.

60 The reinforcement is nearly coextensive in length with the depth of the envelop pocket formed by the said walls 4 and 5 and the outer faces of its flaps 7 may be gummed or pasted to said walls, as indicated at 9, 65 thus firmly securing the reinforcement in position to stay and strengthen the walls at such point of intersection at the end of the envelop. The envelop is formed with an opening 10 in its fold 8 the reinforcement 70 is formed with an opening 11 registering with said opening 10, said openings being preferably disposed at a point about midway of the length of the fold line 8.

75 A fastening member 12 is provided and is inclosed between the folds or flaps of the reinforcement, so as to snugly fit against the fold line 6. This fastening member preferably consists of a single length of wire 80 which is bent upon itself at the middle point to provide a loop or eye 13 which projects externally through the openings 11 and 10, while the ends of the fastening wire are bent or looped back at the extremities of said wire so as to lie on the outer surfaces of 85 and parallel with the wire and provide hooked retaining members 13', which seat at the bends or bights in receiving notches 14 in the ends of the reinforcement and thence extend inwardly over the outer side 90 of said reinforcement parallel with the fold lines 6 and 8 so as to lie between the reinforcement and the end of the envelop. The fastening device is therefore doubly secured 95 in position against any possibility of independent movement, working loose or tearing away from the reinforcement, by which a strong and durable construction of fastening is produced, which at the same time is reinforced, together with the end of the envelop, so as to reduce to the minimum liability of the envelop tearing or the fastener pulling out under imposed strains upon the fastener.

100 In the use of the envelop, it will be understood that the projecting loop or eye 13 is engaged with the usual binder cord or wire, or a supplemental binder cord or wire, attached to the first-named cord or wire, applied about the parcel post package to hold 105

the same sealed or intact, whereby a means is furnished to adapt the envelop to be secured to the package in accordance with the established regulations. It will be observed that the construction of the fastener is not only simple, allowing envelops so equipped to be furnished at a low cost, but that the envelop and fastener are reinforced to a sufficient degree to prevent separation of the parts while the packages being handled are in transit.

In the form of my invention shown in Fig. 5, the construction of the reinforcements and its mode of application is the same as that previously described, but a modified form of fastening member is employed. This fastening member consists of a single length of wire which is bent upon itself or looped to provide a body portion 15 inclosed between the folds of the reinforcement, arms or retaining members 16 lying between the folds 6 and 8 and seated at the bight portions 17 in the notches 14 of the reinforcement, and fastening extremities 18 which project outwardly through the openings 11 and 10, and are preferably coiled or twisted upon themselves, as at 19, so that the parts 15 and 16 will form a closed loop embracing the reinforcement, whereby the parts of the fastener are held fixed and from displacement and any tendency to exert a tearing action on the envelop. The extremities 18 may be passed around the opposite sides or looped about the binder cord of a package and then twisted or otherwise united, or they may be twisted at their ends into a unit, which is looped about the binder cord and then twisted upon itself to hold the envelop applied. This twist by which the ends of extremities 18 are formed into a unit may also be applied to any of the other forms of envelops illustrated herein, and will be found useful in making the opening 10 in fold 8.

In the form of my invention shown in Fig. 6 the construction of the reinforcement and fastener is substantially the same as shown in Fig. 5, except that the body of the wire extends on the outside of the fold 6, while the arms or retaining members 21 extend between the folds of the reinforcement and are thence passed through the opening 11 and formed to provide a loop 22 engaging the body 20, then twisted, as at 23, to form a complete embracing loop, and thence extended outwardly through the opening 10 in the form of fastening extremities 24.

In the form of my invention shown in Fig. 7, a reinforcement 25 of the character disclosed is employed, but the construction of the fastening wire is modified. As shown the central portion of the wire is formed to provide a loop 26 transversely embracing the center of the reinforcement, thence extending from between the flaps of the reinforcement through the opening 11 and bent

to form an eye 27 engaging the bight of the loop, then provided with a retaining twist 28, and thence extended outwardly through the opening 10, to form fastening extremities 29. This form of fastener may be employed whenever the material of the envelop is of a strong or tough character and the use of a fastening extending along the entire length of the reinforcement is not required or desired. 75

In the form of my invention shown in Fig. 8, the construction is the same as that disclosed in Fig. 7, except that the ends of the wire are formed to provide an outwardly projecting eye or loop 30 serving the same purpose as the eye or loop 13 in the construction disclosed in Figs. 1 to 4, inclusive. 80

In the form of my invention shown in Fig. 9, the reinforcement 31 consists of a single-thickness strip of paper or cardboard, and the central portion of the fastening wire is formed to provide a loop 32 centrally embracing said reinforcement, is then formed with a retaining twist 33 which projects through the opening 10 of the envelop, and thence extends outwardly in the form of fastening extremities 34. This form of reinforcement and fastener will be found serviceable in the use of the invention upon envelops of sufficient stiffness or rigidity, and on account of its simplicity will be found effective under many conditions of service. 95

I claim:

1. An envelop comprising front and back portions, a fold line therebetween, a reinforcement coextensive in length with the fold line and comprising a strip of flexible material, said strip being folded medially to provide flaps which bear against said front and back portions on opposite sides of said fold line, the ends of said strip being provided with notches at the terminals of the fold line, and a tying member including a portion extending along the bight of the fold line and engaging said notches, said tying member having a portion projecting beyond the outer surface of the fold line for attaching the envelop to an object. 100

2. An envelop comprising front and back portions, a fold line therebetween, a reinforcement comprising a linear strip of flexible material folded medially to provide flaps which are gummed at the fold line, the fold lines of the walls and reinforcement being provided with registering openings and said reinforcement having notches at its ends in register with the fold line thereof, and a tying member inclosed between the flaps of the reinforcement and extending along the fold line thereof, said tying member having terminal portions engaging said recesses and a portion projecting exteriorly through said openings for attaching the envelop to an object. 115 120 125

3. An envelop comprising front and back 130

portions, a fold line therebetween, a reinforcement comprising a strip of flexible material folded medially to provide flaps which bear against said front and back portions on opposite sides of said fold line, and a tying member having portions extending along and on both sides of said fold line and engaged on the outer side of said fold line and

thence extended to form an element for attaching the envelop to an object. 10

In testimony whereof I affix my signature in presence of two witnesses.

HARRY A. TRUSCOTT.
